UNITED STATES PATENT OFFICE.

HEBER E. HUMBARGER, OF DECATUR, INDIANA.

BUTTER MOLD.

Application filed October 19, 1927. Serial No. 227,183.

The invention relates to devices for molding butter.

In the dairy industry it is necessary to chill butter after it is removed from the churn so that it may solidify for packaging. The practice heretofore generally followed has been to press the butter into very large and heavy cakes and the cakes are then placed in a cooler to chill them. Due to the mass of the 10 cakes they must remain in the cooler a long period of time to become chilled throughout. These chilled cakes are very heavy and are most difficult to cut up into sizes proper to be fed to the printing machine.

15 The object of my invention is to provide novel means by which relatively small cakes of butter suitable for insertion in the print machine are molded and supported for chilling purposes.

20 The invention is illustrated in the accompanying drawings in which,

Figure 1 is a plan view of the mold; Fig. 2 a side elevational view of the same; Fig. 3 a cross-section on line 3—3 of Fig. 2; Fig. 25 4 an end view of the mold in discharging condition; Fig. 5 a side elevational view of the rack; Fig. 6 a fractional plan view of the rack and Fig. 7 a detail view of one of the shelves of the rack.

30 The mold consists of preferably two sides 1 and 2 and two ends 3 and 4, the ends and sides being formed preferably of wood. The bottom of the mold is formed by a portable shelf hereinafter described. The end members are 35 rigidly supported in parallel relation by the tie rods 5 and 5^a and the nuts 6 thereon. The side members 1 and 2 are between the upper tie rods 5 and are hinged to the lower tie rods 5^a by the straps or bars 7 that are secured to the outer faces of said side members and are 40 curved or looped at their lower ends to receive the lower tie rods.

The upper ends of the straps 7 are also 45 curved or looped to receive the rods 8, one strap on each side member being secured to a rod 8 to prevent longitudinal movement of the rods 8 on the straps.

A frame or collar 10 is shaped to fit over 50 the top of the mold and handles 11 are attached to the opposite ends of the frame for convenience in handling. In each end member 12 of the frame are two cam slots 13 which incline inwardly and are adapted to be engaged by the ends of the rods 8. The angle 55 of inclination of the slots is such that when the frame is in its lowermost position, the rods

8 then being at the upper ends of the slots, and the frame is elevated, the slots cause the rods 8 to move outwardly or separate, the side members being rocked outwardly on their 60 hinges.

The mold is placed on one of the shelves of the rack 14, (Fig. 5) about to be described, so that said shelf forms the temporary bottom of the mold.

65 Butter is removed from the churn and packed tightly into the mold, the frame 10 being in its lowermost position. When the mold is filled the frame is elevated to release the side members of the mold whereupon the mold is readily lifted off the molded butter and the cake of molded butter remains on the shelf. The operation is repeated until the shelves of the rack are filled, the rack being 70 then moved into the cooler.

75 The rack 14 is formed of four corner angle bars 15 to the lower portions of which the shelf 16 is suitably secured. Casters 17 may be suitably attached to the bars for convenience in moving the rack. Above the shelf 80 and suitably spaced are any selected number of additional shelves 18, the height of the angle bars and the two additional shelves shown being illustrative only.

85 Each of the additional shelves is hinged at one end to two adjacent corner angle bars and the opposite end of the shelf normally rests on stops or brackets 18^a secured to the other two corner angle bars respectively. Each shelf is preferably formed of metal having a depending flange 19 at each of the four sides thereof. Longitudinal slots 20 are formed in two opposite flanges 19 near one end thereof and a bolt or rod 21 is loosely extended through both slots and through the 90 two adjacent corner angle bars and fixed to the bars by the nuts 22. When the shelf is in horizontal position the bolt is positioned at the outer ends of the slots. Upon swinging the shelf upwardly, as shown in Fig. 5, 100 the shelf drops down until the upper ends of the slots are engaged by the bolt 21. The end of the shelf below the pivot bolt 21 abuts the adjacent corner angle bars and prevents the shelf from rocking to a horizontal position.

105 The shelf, therefore, remains in substantially upright position until it is elevated to cause the bolt to abut the lower ends of the slots 20, whereupon the shelf is swung to a horizontal position in contact with the brackets 18. Each hinged shelf affords 110 ready access to the shelf below for placing the

mold upon it and for removing the mold from the molded cake of butter that remains on the shelf.

It is thus seen that the bottom of the mold 5 is a shelf of a rack and that two opposite walls of the mold are fixed relatively to each other, the other opposite walls being hinged at their lower portions so that they will swing outwardly to release the cake of butter formed 10 on the bottom and between the said four walls.

The mold is highly sanitary and is readily taken apart for a thorough cleaning by merely removing the outer nut 6 on one end 15 of each tie rod. The temporary bottoms 16, 18 being formed of sheet metal are also readily cleaned.

The cakes of butter, being relatively small and of a size to be received by the printing machine, are readily cooled and handled so 20 that much time and labor are saved in the industry.

What I claim is:

1. A butter mold consisting of a portable bottom, two upright walls adapted to be 25 movably supported on the bottom, members secured to said walls to fix said walls in spaced relation, side walls pivotally mounted on some of said members and a movable member about the upper portions of the walls and

having connections with the side walls and 30 adapted when said movable member is moved in a vertical plane to cause said side walls to swing in opposite directions.

2. A butter mold comprising two spaced 35 end walls, a plurality of members connected to both walls, two side walls pivotally mounted at their lower portions on some of said members for lateral swinging movement, each side wall having projecting means on the outer face thereof and a movable frame 40 having cam slots therein engaged by said projecting means whereby when the frame is moved in selected direction the side walls are caused to swing in opposite directions.

3. A butter mold comprising two spaced 45 end walls, a plurality of rods extending through both said walls and secured thereto, side walls pivotally mounted at their lower portions to some of said rods, each side wall near its upper edge having a rod supported 50 thereon, the ends of which rod project beyond the ends of the said wall and a movable frame about the ends and sides having cam slots 55 therein engaged by the projecting ends of the rods.

In witness whereof I have hereunto signed my name this 13th day of October, 1927.

HEBER E. HUMBARGER.
